F. G. CREED

TELEGRAPHIC RECEIVING APPARATUS

Filed March 15, 1920

Fig. 1.

Frank G. Creed
By David Davis, atty.

UNITED STATES PATENT OFFICE.

FREDERICK GEORGE CREED, OF CROYDON, ENGLAND.

TELEGRAPHIC RECEIVING APPARATUS.

Application filed March 15, 1920. Serial No. 366,007.

To all whom it may concern:

Be it known that I, FREDERICK GEORGE CREED, a subject of the King of Great Britain and Ireland, residing at Croydon, in the 5 county of Surrey, England, have invented Improvements in or Relating to Telegraphic Receiving Apparatus, of which the following is a specification.

This invention has reference to telegraphic receiving apparatus of the type designed to perforate telegraph tape in accordance with the Morse code in order to reproduce true Wheatstone or other tape the characteristic features of which is that 10 the dots and dashes or other signals of the code are represented by perforations in the tape, accurately spaced in relation to a central row of feed holes in the tape, each hole, representing a dot, dash or other signal, or 15 part thereof, being placed either transversely opposite or in some other fixed relation to a feed hole in the tape.

For producing such tape, the telegraphic receiving apparatus comprises (a) means 20 for guiding and for perforating the tape embodying a suitable framework and punches mounted therein; (b) means for feeding the tape in an endways forward direction past the punches at a rate corresponding 25 more or less exactly to the speed at which the transmitting tape at a distant sending station passes through the telegraphic transmitter at that station; (c) means for correcting the position of the receiving tape 30 lengthways with relation to the punches before punching the tape and (d) driving means, actuated from a suitable source of power, for actuating the punches, for feeding the tape forward and for correcting the 35 position of the tape lengthways, should this be necessary, before the punching takes place.

Different means have heretofore been proposed for feeding the tape forward and correcting its position lengthways to ensure 40 accurate alignment of the punched holes with the feed holes in the tape.

For instance, in a telegraphic perforating receiver of the type generally known as a 45 Creed perforator, see for example, the specifications of former British Letters Patent Nos. 2834 of 1901; 1061 of 1902; 5490 of 50 1905 and 23834 of 1908, the tape is fed forward by a frictionally driven toothed feed

wheel with which are associated one or two 55 toothed correcting wheels fixed on the feed wheel spindle, and one or more correcting rods adapted to be moved into engagement with the correcting wheel, or with one or other of the correcting wheels if two are 60 used, before punching, so as to adjust the feed wheel and thereby the position of the tape lengthways, should this be necessary before each punch commences to perforate 65 the tape. The teeth of the correcting wheel, or each correcting wheel, are usually made of V shape, and the co-acting end of the corresponding correcting rod, is also made of V or chisel shape.

In perforating receivers of this type in 70 which the correcting means used for ensuring accurate positioning of the tape before punching takes place, is arranged to be positively moved into the operative position by 75 actuating mechanism having a definite and invariable stroke or movement there is a liability, under certain circumstances, of interference with the proper working of the receiver as will appear from the following 80 description.

In the ordinary working of a telegraph circuit, it is always possible at any time for 85 a signal to be received at such a time, or so distorted, that the mechanism used for positively effecting the movement of the correcting rod or rods and punches, or a 90 particular part of such mechanism, as for example an escapement device, would be operated at a moment when the pointed end of the correcting rod, or of one of such rods, when two are used, would exactly correspond with the top or tip of a tooth of the correcting wheel, or corresponding correcting wheel. The effect of this would be to break some part of the mechanism, or to 95 cause stoppage of the mechanism used to operate the correcting rod and punch, with consequent complete loss of all succeeding signals.

It is true that if the teeth of the correcting wheel and that of the correcting rod 100 were perfectly sharp and perfectly aligned, it would be nearly impossible for such a thing to happen as that just described, but, as in practice, these teeth become worn and 105 are seldom in perfect alignment, it is very probable that the machine would not be working long under ordinary conditions,

before a complete stoppage, such as described above, would take place, causing a loss of time and possible loss of traffic before the operator in attendance could 5 start the machine.

Now the present invention has for its object to render it impossible for the correcting rod, by fouling the top or tip of a tooth of the correcting wheel, or corresponding 10 correcting wheel, to stop the motion of the positively actuated mechanism used to operate the correcting rod at the required time and thereby interfere with the proper working of the receiver under circumstances 15 such as hereinbefore mentioned.

For this purpose there is associated with or incorporated in the correcting rod or each correcting rod and the positively actuated device or mechanism used to positively 20 move it into its operative position, a spring or spring-like device or yielding part the action of which is such that it will offer just sufficient resistance with a reasonable margin, to prevent it being strained under 25 the action of the normal thrust of the correcting rod against its correcting wheel but will yield to a sufficient extent to prevent undue straining or fracture of any other part of the receiver and interference 30 with the proper working of the receiver, should the correcting rod meet with undue resistance, due for instance to its pointed end abutting against the top or tip of one of the teeth of the correcting wheel for any 35 reason.

Such a safety device can be constructed and arranged in various ways. Thus, it may be incorporated in or combined with a rod or link used to reciprocate the 40 correcting rod or each of such rods, or in or with such rod. In such a case the rod or link may comprise two relatively movable portions between which is interposed a compressible spring, for instance a coiled 45 spring, the action of which can be adjusted, as by a nut or nuts, to act, when necessary, in the manner described. Or the spring may be arranged between a rod or link such as mentioned, and a lever used to operate 50 the rod or link. Or a spring-like device may be constituted by a bent Ω shaped part of the rod or link. Or the safety device may be incorporated in the lever or other 55 device or mechanism used for moving the correcting rod into its operative position.

A safety device such as described may, if desired, be associated with each punch and the means used for reciprocating it.

Safety devices according to the invention 60 can advantageously be used in perforating receivers of various kinds in which the correcting rod or each correcting rod, or equivalent device, is moved positively into its operative position by positively 65 actuated means having a definite and in-

variable stroke or movement. Thus, it may be applied to perforating receivers of the type described in the hereinbefore mentioned prior specifications and to other receivers, in which the correcting rods or 70 equivalent, and the punches, are moved into their operative positions, against the action of springs, by positively actuated means having a definite and invariable stroke or movement and are moved into their inoperative positions by the springs, and also to perforating receivers of the kind described in the specification of another application for Letters Patent filed by me of even date herewith Serial No. 366,006 in 80 which both the correcting rod or rods and the punches are moved positively both into their operative positions and into their inoperative positions by actuating means having a definite and invariable stroke or movement and the use of returning springs dispensed with.

The accompanying drawings illustrate, by way of example, two arrangements of safety devices according to the invention. 90

Fig. 1 shows in vertical section, part of a perforating receiver such as described in the specification of the said application for Letters Patent Serial No. 366,006 of even date with the present application, embodying safety devices according to the present invention. Figs. 2 and 3 are side views, at right angles to one another and Fig. 4 an end view, showing, to an enlarged scale, one of the correcting rods and its operating 100 lever with combined safety device. Fig. 5 is a detail view showing a modification.

Referring to Figs. 1 to 4 inclusive, *a* is a tape feed wheel fixed on a spindle *b* driven from a motor operated shaft *b*¹ through worm gearing *b*² and a friction clutch *b*³ for drawing a tape having a central row of feed holes therein through a guideway or race *c*. *d* and *d*¹ are two correcting wheels of the kind referred to, connected to opposite sides of the feed wheel for adjusting the position thereof in a rotary direction when this may become necessary. *e*, *e*¹ are the punches for perforating the tape and *f*, *f*¹ are correcting rods for engagement with the correcting wheels *d*, *d*¹ respectively. 110

The punches *e*, *e*¹ are arranged to be positively operated in each direction by levers *r*², *r*³, and the correcting rods or devices *f*, *f*¹, are also arranged to be positively operated in each direction by levers *s*², *s*³, the said levers being positively oscillated through rollers *r*, *r*¹, *s*, *s*¹, by cam grooves *t*, *t*¹ in a rotary spindle *u*, as described in the said specification Serial No. 366,006 of even date herewith. In this example, each of the two correcting rods or devices *f*, *f*¹, which is guided in a stationary part A of the apparatus, is connected to a rod *v* or *v*¹ 125 130

by which it is connected to its cam operated lever s^2 or s^3 .

In order to make it impossible for the pointed end f^2 of each correcting rod or device f , f^1 , by fouling the top or tip of a tooth of the corresponding correcting wheel d , d^1 , to stop the rotation of the spindle u and thereby interrupt the working of the receiver, there is associated with the said 10 correcting rod and the corresponding cam operated levers s^2 or s^3 used for positively actuating it, a safety device that will, under the circumstances mentioned occurring, yield to a sufficient extent to avoid damage 15 or stoppage of the receiver. For this purpose, in the example now being described, each rod v or v^1 has associated therewith a compressible device shown as a coiled spring m , through which it is operated by 20 the corresponding lever s^2 or s^3 . The strength of the spring is such, or which can be made such by adjustment, as by lock-nuts w on the rod, that it is just sufficient, with a reasonable margin, to resist the normal 25 thrust of the correcting rod against the correcting wheel, but will yield to the necessary extent under the pressure of the corresponding cam operated lever s^2 or s^3 , if it meets with undue resistance, due to the point 30 f^2 of correcting rod fouling the top or tip of a tooth of the correcting wheel, the end of the lever s^2 or s^3 then sliding on the end of the rod v or v^1 . For this purpose, normally, the end of the lever is engaged between 35 a collar v^2 fast on the rod and a collar v^3 loose on the rod and pressed against the lever by the coiled spring m (see Figs. 1, 2 and 3).

A similar safety device could, if desired, 40 also be provided on the rod x or x^1 connecting each punch e or e^1 with its corresponding actuating lever r^2 or r^3 .

Fig. 5 shows another arrangement of safety device according to which the rod or link v connected to the correcting rod or device f , is provided with a bent Ω shaped spring part v^4 that is sufficiently stiff to transmit the normal thrust of the rod due to the operating lever s^2 but will yield when 45 the forward end of the correcting rod or device is arrested by abutment against the top or tip of a tooth of the correcting wheel. In this case the collar v^3 is fixed on the rod u .

The correcting rod or rods, and also the punch or punches, could obviously be caused to make their operative strokes by positively actuated means corresponding to or equivalent to, those described, against the 50 action of springs for effecting their return movements but it is preferred to actuate them in both directions positively as described.

Having now particularly described and 55 ascertained the nature of my said inven-

tion and in what manner the same is to be performed I declare that what I claim is:

1. In tape perforating apparatus, the combination with a tape feed wheel, a punch, means for reciprocating said punch, a toothed 70 correcting wheel adapted to adjust said feed wheel in a rotary direction and a correcting device adapted to co-act with said correcting wheel before said punch completes its operative stroke, of mechanically operated driving mechanism and actuating means positively moved by said driving mechanism and adapted to cause said correcting device to make its operative stroke, said actuating means being adapted to yield in the event 80 of said correcting device fouling the top of a tooth of the correcting wheel when making its operative stroke, substantially as described for the purpose set forth.

2. In tape perforating apparatus, the combination with a tape feed wheel, a punch, means for reciprocating said punch, a toothed correcting wheel adapted to adjust said feed wheel in a rotary direction and a correcting device adapted to co-act with said 90 correcting wheel before said punch completes its operative stroke, of mechanically operated driving mechanism and actuating means for said correcting device, said actuating means being positively moved by said driving mechanism independently of said punch and comprising relatively movable parts adapted normally to move together as one part but one of which is capable of movement in relation to the other in the event of the latter being arrested by contact with the top of a tooth of the correcting wheels, when making its operative stroke.

3. In tape perforating apparatus, the combination with a tape feed wheel, a punch, means for reciprocating said punch, a toothed correcting wheel adapted to adjust said feed wheel in a rotary direction and a correcting device adapted to co-act with said 105 correcting wheel before said punch completes its operative stroke, of mechanically operated driving mechanism actuating means positively moved by said driving mechanism and having a definite and invariable movement and correcting means arranged between said actuating means and correcting device and adapted normally to transmit motion from the former to the latter but to yield in the event of the correcting device fouling the top of a tooth of the 110 correcting wheel when making its operative stroke.

4. In tape perforating apparatus, the combination with a feed wheel, a punch for perforating a tape fed forward by said feed 125 wheel, means for reciprocating said punch, a toothed correcting wheel adapted to adjust said feed wheel in a rotary direction before said punch completes its operative stroke, and a correcting device adapted to 130

co-act with said correcting wheel, of a lever, means for oscillating said lever through a definite angle, a spring arranged between said lever and correcting device and adapted to transmit motion from the former to the latter but to yield in the event of the latter being arrested by the top of a tooth of the correcting wheel when making its operative stroke.

10 5. In tape perforating apparatus, the combination with a tape feed wheel, a correcting wheel for adjusting the position of said feed wheel in a rotary direction and a reciprocatory correcting device arranged to co-act with said correcting wheel, of mechanically operated driving means, actuating means positively moved by said driving means and having a definite and invariable movement and arranged between said correcting device and operating means, connecting means adapted positively to move said correcting device into its operative and inoperative positions and to yield should the correcting device be arrested by the correcting wheel before completing its operative stroke.

6. In tape perforating apparatus, the combination with a tape feed wheel, a correcting wheel for adjusting the position of said

feed wheel in a rotary direction and a reciprocatory correcting device arranged to co-act with said correcting wheel, of a rotary cam device, a lever arranged to be oscillated thereby, a rod connected to said correcting device and adapted to be reciprocated by said lever and yielding means associated with said rod and adapted to permit of its being arrested on its forward stroke by the correcting wheel without affecting the forward movement of said lever.

7. In tape perforating apparatus, the combination with a tape feed wheel, a correcting wheel for adjusting the position of said feed wheel in a rotary direction and a reciprocatory correcting device arranged to co-act with said correcting wheel, of a rotary cam device, a lever arm arranged to be oscillated thereby, a rod connected to said correcting device and extending freely through said lever arm and adapted to co-act with the remote side thereof, an abutment on said rod between the correcting rod and said lever arm and a coiled spring arranged between said abutment and the adjacent side of said lever arm.

Signed at London, England, this 2nd day of March, 1920.

FREDERICK GEORGE CREED.
